UNITED STATES PATENT OFFICE.

FRED W. LAPIENS, OF MARION, TEXAS.

BELL ATTACHMENT.

1,294,122.

Specification of Letters Patent. Patented Feb. 11, 1913.

Application filed September 28, 1917. Serial No. 193,805.

To all whom it may concern:

Be it known that I, FRED W. LAPIENS, a subject of the Emperor of Germany, residing at Marion, in the county of Guadalupe and 5 State of Texas, have invented new and useful Improvements in Bell Attachments, of which the following is a specification.

This invention comprehends the provision of a bell attachment, and while the invention 10 is shown and described in connection with telephone bells, because it constitutes one of its most useful applications, it is desired to have it understood that its general application is contemplated by the claims.

15 The invention aims to provide an attachment for bells which causes the latter to render a softer and more pleasing sound, than it does under ordinary conditions, the sound being at the same time sufficiently loud for 20 telephone service, or for use in other capacities as a signal.

The nature and advantages of the invention will be better understood when the following detail description is read in connection 25 with the accompanying drawing, the invention residing in the construction, combination and arrangement of parts as claimed.

In the drawing forming part of this specification like numerals of reference indicate 30 similar parts in the several views and wherein:

Figure 1 is a perspective view of a telephone, the bells of which are provided with my invention.

35 Fig. 2 is a sectional view through the telephone and one of the bells.

Fig. 3 is a perspective view of the attachment with the parts separated.

In the drawing 10 indicates an ordinary 40 telephone which embodies the usual electrically operated hammer 11 that is adapted to strike between the bells 12. If desired the hammer 11 may be provided with a sleeve 13 of rubber or other suitable material 45 to prevent the metal hammer from contacting the bell, with a view of producing a softer tone. The sleeve 13 is primarily intended for use when the bell or bells 12 are not equipped with the attachment to be 50 presently described, although the same may be employed with bells equipped with the attachment as shown. The bells 12 are attached to the telephone in the usual manner by means of a post 14. While reference is 55 made to two bells, it is to be understood that

the phone may be equipped with a single bell, in which instance the hammer 11 may operate within the bell or from the exterior thereof.

The attachment for said bells embodies an 60 elongated member 15 which may be constructed from any suitable material, and provided with a central opening 16 for the reception of the post 14 upon which the member is mounted. The member 15 is 65 slightly bowed or curved longitudinally so that the extremities of the member are wholly disposed within the bell 12 as clearly shown in Fig. 2, while fitted upon the post is a plurality of washers or gaskets 17, the 70 latter being interposed between the telephone 10 and the intermediate portion of the member 15 against the latter to maintain the member properly positioned within the bell. In other words the washers 17 maintain the 75 member 15 engaged with the bell for the purpose intended, in which position the member is prohibited from becoming casually deranged. An endless band 18 of rubber or other suitable material is fitted upon 80 the member 15 wholly enveloping the latter, and consequently being disposed in direct contact with the bell 12. The band 18 is of such material that will tend to soften the sound of the bell when struck by the hammer 11, thus causing the bell to render a 85 sound which is more pleasing to the ear, and yet sufficiently loud to permit use of the bell in the capacity of a signal or indicator. The parallel portions 19 of the band are 90 provided with aligned openings 20 through which the post 14 is extended, the openings 20 of course registering with the openings 16 in the member 15. In contradistinction to the employment of an endless band 18, if desired the terminals of the member 15 need only be covered with suitable material to 95 soften the sound when the signal is sounded. The invention is not only simple in construction with a consequent cheapness of manufacture, but is designed so that bells in common use may be readily and easily equipped with the same.

While it is believed that from the foregoing description the nature and advantages of the invention will be readily apparent, I desire to have it understood that I do not limit myself to the precise construction and arrangement of parts herein shown, as the same is merely illustrative of one embodiment.

ment of the invention, and that such changes may be resorted to when desired as fall within the scope of what is claimed.

What is claimed is:—

5 1. A bell attachment comprising an elongated member, an endless band enveloping said member, and said member and band being disposed with its terminals in contacting engagement with the bell for the purpose
10 described.

2. The combination with a bell, and a post supporting the latter, of an elongated member having an opening to receive the post, an endless band of relatively soft material enveloping said member, and means for 15 maintaining said member positioned with respect to the bell whereby the terminals of the member contact the latter.

In testimony whereof I affix my signature.

FRED W. LAPIENS.
